CLAIM

The ornamental design for a high bay light, as shown and described.

DESCRIPTION

FIG. 1 is a front perspective view of a high bay light design showing my new design.

FIG. 2 is a rear perspective view of the high bay light.

FIG. 3 is a front view of the high bay light.

FIG. 4 is a rear view of the high bay light.

FIG. 5 is a left side view of the high bay light.

FIG. 6 is a right side view of the high bay light.

FIG. 7 is a top view of the high bay light; and,

FIG. 8 is a bottom view of the high bay light.

Any shading and cross-hatching are not features of the design but are utilized to illustrate the surface contours of the high bay light design in the drawings.

The broken lines in the drawings illustrate portions of the high bay light and form no part of the claimed design.
